UNITED STATES PATENT OFFICE.

JAMES A. WHITNEY, OF DOBBS FERRY, NEW YORK.

MACHINE FOR MANUFACTURING PILLS, &c.

SPECIFICATION forming part of Letters Patent No. 256,420, dated April 11, 1882.

Application filed September 16, 1881. (No model.)

To all whom it may concern:

Be it known that I, JAMES A. WHITNEY, late of the city, county, and State of New York, and now residing at Dobbs Ferry, (otherwise known as Greenburg,) in the county of Westchester, in said State of New York, have invented certain Improvements in Machines for the Manufacture of Pills, &c., of which the following is a specification.

This invention comprises certain novel combinations of parts whereby the operations of forming or shaping pills from sheets or portions of pill-mass are greatly facilitated, and whereby the avoidance of casual hinderances to the perfect performance of said operations is effectually secured.

Figure 1 is a plan view of the machine embraced in my said invention. Figs. 2 and 3 are detail views of certain parts included in said machine. Fig. 4 is a vertical longitudinal sectional view of my said machine, taken in the line *xx* of Fig. 1. Fig. 5 is a vertical transverse sectional view of said machine, taken in the line *yy* of Fig. 1. Fig. 6 is a detail view of certain parts included in said machine. Figs. 7 and 8 are front views illustrating the manner in which certain parts are manipulated in the use and operation of the said machine. Figs. 9, 10, 11, and 12 are detail views of different portions of said machine. Figs. 1 to 8, inclusive, are drawn to a scale of two inches to the foot. Figs. 9 to 12, inclusive, are drawn to a scale of five inches to the foot.

The working parts of the apparatus are sustained by a suitable horizontal frame, *A*, which is itself appropriately supported—as, for example, upon legs or standards *B*.

C is a plate placed upon one end of the frame *A*, and having two hinge-arms, *a*, which are pivoted at *b* to the frame *A*. This plate *C* should have an outwardly-projecting handle, *a'*, by which it may be turned upward and around its pivots *b*. This plate *C* has its upper surface slightly grooved or corrugated in a direction parallel with its axis of movement around its pivots *b*. The grooves should be arc-shaped in their cross-section, and the ridges which divide them should be coincident with those of the roller *D*, hereinafter described. The grooves in the said plate *C* are designed to be comparatively shallow—that is to say, the ridges between them are intended to penetrate

less than one-half way through the thickness of the sheet or layer of mass placed upon the said plate preparatory to the formation of the cylindrical strips from which the pills are ultimately formed, the object of said grooves in said plate *C* being to prevent the mass from casually slipping laterally out of place, as in some instances is liable to occur where the said plate *C* is formed with an entirely plane surface.

E is another flat plate, the upper surface of which is grooved in directions parallel with the hereinbefore-indicated axis of movement of the plate *C*. The grooves in this plate *E*, however, are intended to be of such a depth that the ridges between them will extend substantially half-way through the sheet of pill-mass operated upon, the said grooves in said plate *E* being of semi-cylindrical cross-section, with the ridges formed by the edges of the semi-cylindrical grooves sharp-edged or acute, the grooves themselves being of a uniform depth and width, both width and depth being proportioned to the size of the strips of pill-mass to be formed upon the said plate, as hereinafter explained. This plate *E* is provided at its left-hand lateral edges with two hinge-arms, *c*, which are connected at their outer extremities by a rod, *d*, which, when the plate is in its horizontal position, rests in deeply-notched bearings *e*. Provided upon the opposite side of the plate *E* are two other hinge-arms, *f*, each of which is provided with a stud or pin, *g*, projecting outward therefrom. These studs or pins *g*, when the plate *E* is in its horizontal position, rest in deeply-notched bearings *h* on the frame *A*. The forward one of the hinge-arms *f* should be provided with a handle, *i*. When in its horizontal position the plate *E* is supported by the aforesaid notched bearings *e* and *h*, the rod *d* being axially coincident with the pivots *b* or axis of movement of the plate *C*. The plate *E* may be turned over around upon the bearings of its shaft *d* until it is brought over and upon the plate *C*. In like manner the plate *C* may be turned over upon its pivots *b* until it is brought over and upon the plate *E*. When the said two plates *C* and *E* are brought together the grooves on their respective upper surfaces are opposite to and coincident with each other, the grooves of the one plate being coincident with the

grooves of the other. When thus brought together the two plates may be simultaneously turned upon their common axes of movement—viz., the axes of the pivots *b* and shaft *d*.

- 5 F is a third plate, which rests upon and is supported by the flat adjacent upper surface of the frame A, and which has projecting from its inner end hinge-arms K, which are pivoted to bearings *l* suitably provided upon the frame 70 A, the said bearings *l* being axially coincident with the bearings *g* of the plate E, so that the plate E may be turned over upon the plate F, or the plate F over upon the plate E, or both moved together and simultaneously. To enable the plate F to be thus manipulated it should be provided with a handle, *m*. The plate F has its upper surface grooved in a direction at right angles to the direction of the grooves in the plates C and E. These grooves 75 in the plate F have a cross-section of a width, depth, and shape corresponding to that desired to be given to the completed pills. Thus, for example, if the pills are to be spherical, the grooves of said plate F will be semi-cylindrical 80 and of the same width and depth as the grooves of the plate E, whereas, if the pills are to be oval or oblong, the grooves in said plate F will be semi-oval in cross-section, so that said grooves, in conjunction with those of the plate 85 25 F³, hereinafter described, will present a cross-section corresponding to the longitudinal section of the finished pill. Their depth, however, should not materially differ from the depth of the grooves in the plate E.
- 30 D and G are two rollers, the journals of which work in suitable boxes, *r*, provided to a carrier-bar, H, which receives a to-and-fro movement by means of a crank, I, connected with it by a connecting-rod, J. The bearings *r* of these 90 35 two rollers should be made vertically adjustable by threaded shanks *a'* and jam-nuts *b'* *b''*, suitably arranged in relation to the carrier-bar H. The roller D is circumferentially grooved, the grooves being substantially semicircular 95 40 in their cross-section. When this roller is rolled over the plate C, as hereinafter explained, the grooves of said roller are coincident with the grooves in the said plate C. It is intended that these grooves of the roller D shall not 100 45 only be substantially semicircular in cross-section, but that the ridges between them shall be somewhat higher or more extended than is necessary to a true semicircular cross-section to the grooves themselves, in order that when 105 50 the mass upon the plate C is acted upon by the roller D the ridges between the grooves, cutting into the upper side of the mass, as hereinafter explained, shall extend somewhat more than half-way through the thickness of 110 55 the sheet of mass. The roller G is also circumferentially grooved in substantially the same manner as the roller D the grooves of the said roller G being coincident with the grooves of the plate E when the said roller is moved 115 60 over the said plate, as hereinafter explained. The grooves in the roller G may, when pre-

ferred, be of a depth a trifle more than that afforded by a true semicircular cross-section, in order that the sharp edges of the ridges between the grooves may more effectually insure 70 a thorough cutting or separation of the mass into strips, as hereinafter more fully indicated. Inasmuch as it is desirable that the cutting action of the rollers D and G upon the mass, whether the same be upon the plate C or upon 75 the plate E, should be gradually exerted, provision is made for the gradual lowering of the said rollers upon the said plates as the rollers are moved to and fro over said plates by the action of the crank I.

80 Provided in the end of the frame A adjacent to the outer end of the plate C is a deep vertical recess or socket in which is placed a guide-rail, L, the said guide-rail being held in a proper position in said recesses or sockets, 85 and resting upon the upper side of a bar, M, placed parallel underneath the same. This bar works through inclined slots formed in fixed blocks or bearings P. Through the inclined slots of the said blocks or bearings P pass the 90 angles or inclines *n* of a bar, M, in such manner that when the said bar is pushed forward the angles or inclines *n* will elevate the said bar throughout its length, and thereby raise the rail L, and when the said bar M is moved backward the said angles or inclines, acting upon the well-known principle of an inclined plane, will cause the said bar, and consequently the said rail L, to descend, the arrangement of these parts being more fully shown in Fig. 9. 95 Clasps *s*, attached to the rail by bolts or screws *s''*, may pass underneath the bar M to more firmly connect the two. Any endwise movement of the rail is prevented by adjacent fixed cleats *s'''*.

100 The plate E, at its edge adjacent to the plate F, is provided with an extension, *w*, in which is formed a vertical groove, recess, or socket substantially identical in shape and diameter with that just hereinbefore described as situated at the outer end of the frame A, and in this socket of the plate E is placed another guide-rail, L, together with another bar, M, having angles or inclines *n*, and which itself passes through blocks or bearings P¹¹ corresponding to the blocks or bearings P, but provided to the aforesaid part of the said plate E, instead of the frame A, as represented in Fig. 5, this second bar, M, and rail L being operated, by means hereinafter set forth, in the same 110 manner as and simultaneous with the others just specified herein. The upper edge of each rail L is tongued, as shown at *c'*.

115 Upon the outer end of the shaft of the roller D is placed a grooved wheel, N, which runs 120 upon the adjacent rail L, the groove of the said wheel N receiving the tongue of the said rail. In like manner the outer end of the shaft of the roller G is provided with another grooved wheel, N, which in like manner runs upon its 125 adjacent rail L, the groove of the roller fitting upon and receiving the tongue of the said rail,

so that by this means the grooves of the said rollers D and G are kept coincident with the grooves of the respective plates C and E as the rollers pass to and fro over them. When the bars M are moved forward to lift the rails L, as hereinbefore explained, the rollers D and G, in passing over the plates C and E, will be held at an appreciable distance therefrom, and in proportion as the bars M are moved backward to permit the rails L to descend, just in the same proportion will the rollers D and G be let down toward the surface of the plates C and E until the flanges a'' of the rollers rest upon narrow flat edge portions b'' provided to the plates, which done, the ridges of the roller G will be substantially in contact with those of the plate E, but practically without danger of the two sets of ridges abrading or crushing each other. By this regular descent of the said rollers upon the mass as the same lies on the plates the action of the parts upon the mass to divide the same is rendered gradual and positive.

In order to secure the requisite movement of the bars M, there is placed at a slight distance behind them a rock-shaft, P', provided with two vertical arms, Q, the upper ends of which are behind but at a slight distance from the rearmost ends of the two bars M. Interposed between the upper end of one arm Q and the rearmost end of the adjacent bar M is a sliding block, R. Underneath each bar M is a spring, f', one end of which is attached to one of the braces, S, which forms part of the frame A, and the other to the bar M itself, so as to tend to draw the said bar backward, this, of course, tending to throw backward the arms Q of the rock-shaft P'. A sliding bar, T, working in suitable guides, g', has one of its ends in contact with the rearmost side of the upper extremity of one of the arms Q of said rock-shaft P', while the opposite or rearmost end of said sliding bar T is in contact with the circumference of a graduated cam, U, a spring, h', being applied to the bar T to press its said rearmost end against the said circumference of said graduated cam U. This cam has its circumference cut into a number of successive steps, each succeeding step being at a lesser distance from the axis of movement of the said cam, in order that the bars M may be permitted to descend at intervals, as hereinafter explained, the said cam also being so shaped that after the bars M have reached the limit of their rearward stroke the sliding bars T, and consequently the bars M, will suddenly be thrown forward to lift the rails L, and consequently the rollers D and G.

Provided upon the frame A in rear of the plates C and E, and substantially on a level with them, is a table or platform, A⁵, and the throw of the crank I is so proportioned that at each rearward stroke thereof it brings the rollers D and G upon said platform and clear of the plates C and E, so that when the motion of the machine is stopped with said rollers on said platform room is afforded for the turning

movement of the said plates, as hereinafter explained.

The shaft V of the cam U works in suitable bearings, i', provided on the frame A, and is connected by a spur-wheel, W, and pinion w' with the shaft A' of the crank I. This shaft A' is connected by beveled pinions B' and C' with the driving-shaft D'.

Fixed upon the frame A, upon each side of the plate F, but at such distance therefrom as not to interfere with the hereinbefore-indicated movement of the said plate, are inclined bearings, which, for convenience of description, I term "inclined planes," E', and which are shown in cross-section in Fig. 9 and indicated in side view in Fig. 7. These inclined planes are longitudinally tongued on their upper sides, as shown at m, to receive a correspondingly-shaped groove formed on a sliding bar, which, for convenience of description, I term a "moving inclined plane," F'', the slope of the under side thereof being opposite to that of the inclined plane E', as represented in Fig. 7 aforesaid. These inclines F'' are connected at their outer ends by a cross-piece, G'', so that the two may move in unison.

In order that the inclines F'' may not be lifted from their places in the operation of the machine, as hereinafter explained, there is attached to the outer side of each a cheek piece or plate, H'', upon the lower inner edge of which is formed a spline, f'', which fits into a groove, g'', formed in the outer side of the adjacent inclined plane E', and extending parallel with the slope of the said inclined plane E'. In order to further steady the movement of the inclined planes F'' upon the inclined planes E', there is extended from each of the latter to the adjacent parts of the frame A a spiral spring, I'', which also serves the additional purpose of tending to draw backward or outward the inclined planes F'' to keep the bar J'' of the cross-piece G'' in contact with the cam G', the shaft H' of which works in suitable bearings, h'', provided on the frame A, and which has at its outer end a spur-wheel, K', which gears into a spur-pinion, K'', on the adjacent end of the driving-shaft D'. Each of the inclined planes F'' is longitudinally grooved in its upper edge, the said upper edge being substantially level—that is to say, in a plane parallel with the plane occupied by the plates C, E, and F. These grooves receive tongues L'' formed longitudinally on the under sides of the side bars, M'', of a carriage, R', the side pieces, M'', being connected by a cross-piece, R'', of such conformation as not to interfere in its movements with the other and adjacent parts of the apparatus. This cross-bar R'' is provided underneath with lugs r'', which permit the attachment, by means of a cross-pin, s'', of a pitman, S'', which, as shown in Fig. 4, connects with an eccentric, T', on a counter-shaft, T'', which, by means of a pinion, (shown in dotted outline at m'' in Fig. 4,) is driven from a spur-wheel, u'', on the driving-shaft D'.

60 with them, is a table or platform, A⁵, and the throw of the crank I is so proportioned that at each rearward stroke thereof it brings the rollers D and G upon said platform and clear of the plates C and E, so that when the motion of the machine is stopped with said rollers on said platform room is afforded for the turning

T^3 is a plate, the under side of which is formed with semicircular grooves corresponding in depth, width, and contour to the grooves in the plate F , and which, as more fully shown at c^4 in Fig. 10, is hinged at one edge to the adjacent side pieces, M'' , in such manner that the plate F^3 can be thrown over and away from the plate F , or be brought down over the same in a position parallel therewith, and there retained by means of a suitable bolt or spring-catch, w''' , which holds into a cavity formed in due relation thereto in the inner edge of the opposite side bar, M'' . The plate F^3 being carried by the carriage R' and the latter receiving a vibratory motion from the cam T' , it follows that the plate F^3 will be moved to and fro over the plate F , and inasmuch as the grooves of the plate F^3 are coincident with those of the plate F , cylindrical strips of pill-mass placed between the two plates transversely to the grooves thereof will be rolled over and over and divided into pills circular in cross-section, and having a longitudinal section corresponding to that of the coincident grooves of the plates F and F^3 , this operation being performed as the two plates aforesaid approach each other, and the mass is subjected to the cutting action of the ridges of the two plates, respectively, and the shaping action of the surfaces of the grooves thereof.

It is also to be observed that inasmuch as the side pieces, M'' , of the carriage R' move longitudinally upon the upper surfaces of the inclined planes F'' , and these latter move upon the coincident inclined planes E' , it follows that as the inclines F'' are pulled backward by the springs I'' against the cam G and the said cam rotated in the direction indicated by the arrow in Fig. 4 the said cam G will first move forward the inclines F'' to raise the carriage R' , and consequently the plate F^3 , and then backward to lower the said carriage and plate, the carriage being raised or lowered, according as one or the other portion of the said cam is acting upon the bearing f'' of the cross-bar G'' of the inclined planes F'' , provision being made for raising the plate F^3 to such a distance from the plate F that the strips of pill-mass may not be crushed when first placed between the said plates, and for then gradually lowering the plate F^3 simultaneously with its vibratory motion, in order that the operation of separating the strips into pills may be performed by the gradual descent of the plate F^3 to the plate F during the aforesaid vibratory motion of the plate F^3 .

By releasing the catch w''' the plate F^3 may be thrown upward and backward clear of the plate F , in which case it may rest against the cross-piece x' of a suitable standard, z' , which latter is attached to the adjacent portion of the frame A .

In order to stop the motion of the machine at will, the pulley D^3 on the driving-shaft D' is connected with the latter by means of a suitable clutch, E^3 , operated by a shipping-lever,

G^3 , the opposite end of which works between two studs, a^3 , on a sliding bar, H^3 , which is placed in suitable guides on the frame A , and which, passing under that portion of the said frame which supports the plate E , projects beyond the front of the apparatus, and is provided with a suitable handle, b^3 , by which it may be moved backward or forward. A spring, c^3 , is of sufficient tension, when permitted to act, to throw the clutch out of gear with the pulley D^3 in order to stop the machine. By pushing the rod H^3 inward the clutch connects the pulley D^3 with the shaft D' , thereby putting the machine in motion. The rearmost or inner end of the bar H^3 has a notch or shoulder, f^3 , and when the said bar is pushed inward to set the machine in operation this shoulder passes underneath a spring-catch, G^3 , which is shown in detail in Fig. 2, this catch G^3 being pressed downward by a spring, h^3 . A lever, I^3 , connects by a rod, i^3 , with the inner end of the catch G^3 , as more fully represented in said Fig. 2, the said lever I^3 having its rearmost end turned at right angles to its main length, in order that the rod i^3 may more conveniently connect with the aforesaid end of the spring-catch G^3 . This lever I^3 , the fulcrum of which is represented at j^3 , connects by a rod, K^3 , with a treadle, m^3 , so that by pressing down on the forward end of said treadle the spring-catch G^3 will be lifted, thereby releasing the bar H^3 , whereupon the spring c^3 actuates the shipping-lever G^3 to throw the clutch out of gear with the pulley D^3 and stop the motion of the driving-shaft, and consequently of the machine. The apparatus may thus be stopped and started at will. In its ordinary use and operation, however, it is preferable that its motion should be stopped automatically when a full round of its operations has been completed. In order to provide for this there is attached to one end of the shaft V of the cam U a second cam, n^3 , so proportioned that at the completion of each round of the operations of the machine the portion of the circumference of the cam farthest from its axis will act upon the inner end of an arm, f^4 , of the spring-catch G^3 to depress the same in the same manner that the said inner end of the said catch is depressed by the action of the treadle m^3 , thereby releasing the bar H^3 and permitting the spring c^3 to actuate the shipping-lever G^3 to move the clutch E^3 to release the driving-pulley D^3 , and thus stop the motion of the driving-shaft, the machine being started at the commencement of the next round of operations by pushing forward the bar H^3 , as hereinbefore explained.

Inasmuch as it is desirable that after the plate F^3 has been brought down upon the plate F the reciprocating movement of the plate F^3 with reference to the said plate F should be still continued for an appreciable length of time, it is found best in practice that the motion of the cam G' be arrested during a brief interval to permit such movement of the plate F^3 with reference to the plate F .

In order to provide for this the cam G' is loose upon the shaft H' , except when made fast by the action of a clutch, r^3 , placed upon the shaft H' of the said cam. In order to obtain the requisite longitudinal movement of the clutch r^3 , the shaft H' is hollowed to permit the passage of a rod, s^3 , through the same, and its connection by any suitable device with the clutch r^3 , so that a longitudinal movement given to the rod s^3 actuates the said clutch to release the cam G' , or to make the same fast to the shaft H' , as the case may be. The requisite movement of the rod s^3 at the proper intervals is provided for by means of a lever, R^3 , pivoted at u^3 , one end of which said lever is attached to the end of the rod s^3 and the other to the end of a sliding bar, P^3 , which works through suitable guides provided to the frame A , and which has its rearmost extremity pressed against the circumference of a cam, S^3 , on the shaft V , the said bar P^3 being pressed backward against the said cam S^3 by means of a spring, w^3 . The circumferential contour of the cam S^3 is shown in the detail view, Fig. 6. When the bar P^3 is forced inward by the more prominent portion of the cam S^3 the clutch r^3 is operated to make fast the cam G' to the shaft H' , in order that the said cam may act upon the bearing f'' of the cross-piece G'' , in order to provide the requisite vertical movement of the plate F^3 with reference to the plate F . When, however, the recessed portion of the cam S^3 permits the rearward movement of the bar P^3 the lever R^3 is actuated to unclutch the cam G' , thereby causing the shaft H to run loose within the same, and causing the inclines F'' to remain stationary at that stage in the operation of the machine when the plate F^3 has been brought down close upon the plate F , so that the reciprocating movement of the plate F^3 will be continued to more completely finish the operation of rolling and separating the strips into pills by the conjoined action of the said plates F^3 and F when said plates are nearest together.

In the operation of the machine the pill-mass, in the form of a sheet of suitable thickness, is placed upon the plate C , this being done while the rollers D and G are drawn back upon the platform A^5 in rear of the plates C and D . The machine being then put in motion, the roller D moving to and fro over the plate C and being gradually lowered, as hereinbefore described, cuts into the upper surface of the sheet of mass laid upon the plate C , and simultaneous therewith spreads out the mass to any requisite extent, the result being that the upper surface of the sheet of mass is grooved or corrugated by the action of the roller D , the corrugations being substantially semicircular in their cross-section and the grooves being intended to extend somewhat more than half-way through the thickness of the sheet of mass. The said sheet during the last-mentioned operation is held against casual lateral displacement by means of the shallow grooves on the

upper surface of the plate C , the under side of said sheet being forced into the said shallow grooves while its upper side is being acted upon by the roller D , as just described. The operation of grooving or shaping the upper side of the sheet of mass on the plate C being completed, the bar H , with the rollers D and G , is by the automatic stoppage of the machine, as hereinbefore explained, brought over the platform A^5 to permit the manipulation of the plates C and D , as herein presently explained, the rails L being meanwhile lifted preparatory to the next succeeding operation of the rollers D and G . The plate E is then, by means of its handle i , turned over upon the plate C , the grooves of the plate E fitting upon and clasping the corrugations in the sheet of mass as the same lies on the plate C . This done, the handle a' of the plate C is also grasped by the operator, and the two plates, with the sheet of mass clasped between them, are together turned over around the axes of the pivot b and shaft d until the plate E is returned to its horizontal position, whereupon the plate C is turned back to its own horizontal position, leaving the sheet of mass inverted upon the plate E , the plate C being now ready to receive a succeeding sheet of mass to be acted upon by the roller D in the same manner as hereinbefore described. The ridges between the grooves of the plate E being calculated at one-half the thickness of the sheet of mass deposited on the said plate, and the grooves formed in the sheet of mass by the action of the roller D extending somewhat more than half-way through the said sheet, it follows that when the latter is inverted upon the plate E there exists at the under side of said sheet a cavity above each of the ridges between the grooves of the plate E . The machine being again set in operation, the roller G is moved to and fro over the plate E simultaneous with the corresponding movement of the roller D over the plate C , and inasmuch as the ridges between the grooves of the roller G are calculated to cut substantially one-half way through the thickness of the sheet of mass as it lies on the plate E , and inasmuch as the grooves of the roller G are coincident with those of the plate E , it follows that the upper side of the sheet of mass is grooved and corrugated substantially coincident with the grooves and corrugations of the now under side of the sheet of mass, so that when the roller G , as hereinbefore described, has descended until it is substantially in contact with the plate E the mass on the said plate is divided into strips which are of substantially circular cross-section, it being found in practice, however, that the grooves of the rollers D and G and of the plate E may be so formed as to give a very slightly oval cross-section to the strips of mass without materially interfering with the subsequent operation of rolling the strips into pills.

It will be observed that the spaces provided in the under side of the mass above the ridges

of the plate E as the mass lies upon the said plate greatly facilitate the separation of the strips from each other, as fully set forth in my application for a patent on improvement in process and machinery for making pills, allowed, and intended by me to issue in Letters Patent of even date with that which may be issued upon this present specification. When the operation of forming the strips on the plate 10 E is completed the movement of the machine again ceases, the rollers D and G stopping, as before, over or upon the platform A⁵. The plate F³ is then thrown backward around its pivot e⁴ and allowed to rest against the standard x', thereby permitting the plate F³ to be lifted by means of its handle m and turned upward and inward around the axes of the studs g and pivots l until it is brought down upon the plate E, the grooves and ridges of 15 the plate F being transverse to the strips of mass as the latter lie in the grooves of the plate E. The hinge-arms k of the plate F and the hinge-arms e of the plate E are so formed that when the plate F is brought over the 20 plate E, as described, the face of the said plate F will be substantially parallel with the face of the plate E, the two being at such distance apart that the strips of mass are lightly held between them without being crushed or deeply 25 indented by the coincident pressure of the said two plates. The operator grasping simultaneously the shaft d of the plate E and the handle m of the plate F, the two plates F and E, holding the strips of mass between them, are 30 turned upward and over around the axes of the studs g and pivots l, in the manner indicated in Fig. 8, until the plate F is returned to its original horizontal position, whereupon the plate E is turned backward to its own 35 horizontal position, leaving the strips of mass deposited upon the central portion of the plate F, and transversely to the grooves thereof, which done, the plate F³ is brought down to its horizontal position, and there locked by 40 the action of the catch w''. At this stage the plate F³ is held by the inclined planes F'', so that the ridges between its grooves but slightly touch or indent the upper sides of the strips of mass placed between the said plate F³ and the plate F underneath. The strips of mass 45 having been transferred, as described, to the plates F F³ the plates C and D are again manipulated to transfer the sheet of mass from the former to the latter, which being done, another and succeeding sheet is placed upon plate 50 C. The machine being then again set in motion, the reciprocating movement of the plate F³ upon the plate F, combined with the gradually-descending movement of the plate F³ upon the said plate F, causes the strips to be rolled 55 between the two plates until by the coincident action of the ridges and grooves of the plate F³ and the ridges and grooves of the plate F the strips are divided and shaped into pills. 60

65 The most effective and complete separation

of the strips and pills and the more finished form of the latter are insured by the continuance of the reciprocating movement of the plate F³ after its descent upon the plate F has been accomplished, as hereinbefore explained. When the shaping of the pills between the plates F³ and F is completed the machine ceases its motion with the rollers D and G situated, as before, on or over the platform A⁵. The plate F³ is then thrown upward and backward against the standard x', and the plate F being then lifted and turned to receive the next succeeding batch of strips from the plate E, the pills roll off from the plate F as the latter is inclined and are caught in any suitable vessel temporarily held at the inner end of the said plate F to receive them. In the treatment of the pill-mass, as hereinbefore described, it is a matter of judgment to dust the surfaces of the plates C E F and also the surface of the mass with powdered chalk, ground licorice-root, or other innocuous powdered material to prevent the mass from adhering too strongly to the surfaces with which it is brought in contact. 75

It will be observed that the plates C, E, and F and the parts directly co-operating with each are all in operation at the same time, acting upon different sheets or portions of pill-mass at different stages of progress toward the condition of the fully-formed pills, so that a full round of the operations of the machine is completed with each complete grooving and corrugation of the surface of the mass on the plate C, the separation of one portion of mass into strips on the plate E and the separation of another portion in the form of strips into pills on the plate F proceeding simultaneously with the grooving and corrugation of the upper surface of a third portion on the first-mentioned plate C. 90

105 What I claim as my invention is—

1. The combination, with the grooved roller D, of the plate C, constructed with shallow grooves or depressions in its upper surface to prevent casual lateral displacement of the mass during the operation of the grooved roller thereon, substantially as herein set forth. 110

2. The combination, with the grooved roller D and plate C, of means, substantially as described, for graduating the descent of the roller upon the plate during the operation of grooving and corrugating the mass thereon, substantially as herein set forth. 115

3. The combination, with the roller D and plate C, of vertically-movable rails L and means, substantially as described, for raising and lowering said rails to graduate the distance between the said roller and plate, substantially as and for the purpose herein set forth. 120

4. The combination of the rollers D and G, arranged for simultaneous operation, the plates C and E, the vertically-movable rails L, arranged to receive the weight of the rollers, and means, substantially as described, for graduating the vertical movement of the rails to grad- 125 130

uate the distances of the said rollers from the said plates, substantially as herein set forth.

5. The combination, with the rollers D G and the plates C E, of mechanism, substantially as described, for automatically stopping the movement of said rollers at intervals to permit the manipulation of the plates, substantially as and for the purpose herein set forth.

6. The combination, with the plates F F³, inclined planes E' F', and cam G', of mechan-

ism, substantially as described, for stopping the motion of the cam to permit continued motion of the plate F³ after the same has descended to the plate F, substantially as herein set forth.

JAMES A. WHITNEY.
